UNITED STATES PATENT OFFICE.

CHARLES T. WESTLAKE, OF ST. LOUIS, MISSOURI, ASSIGNOR TO COMMONWEALTH STEEL COMPANY, OF ST. LOUIS, MISSOURI, A CORPORATION OF NEW JERSEY.

CAR-TRUCK.

1,385,737.

Specification of Letters Patent. Patented July 26, 1921.

Application filed July 25, 1919. Serial No. 313,288.

To all whom it may concern:

Be it known that I, CHARLES T. WESTLAKE, a citizen of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawing, forming part of this specification.

My invention relates to new and useful improvements in car trucks of the type having pivoted side frames, the principal objects of my invention being to generally improve upon and simplify the construction of this type of truck; and to provide means for distributing the load of the car on the journals.

With the foregoing and other objects in view, my invention consists in certain novel features of construction and arrangement of parts, hereinafter more fully described and claimed, and illustrated in the accompanying drawings, in which—

Figure 1 is a plan view of a car truck of my improved construction.

Fig. 2 is a cross section taken approximately on the line 2—2 of Fig. 1.

Fig. 3 is a detail section taken approximately on the line 3—3 of Fig. 2.

Referring by numerals to the accompanying drawings, which illustrate a practical embodiment of my invention, 10, 10 designate wheel carrying axles, the ends thereof being arranged in the usual manner in journal boxes 11, and which latter are arranged in journal box openings formed in truck side frames 12. These side frames are preferably cast and are provided on their ends with brackets 13 which serve as supports and points of connection for the hangers of outside hung brake beams 14. These side frames 12 are tied together by a centrally arranged member 15, the ends thereof being seated in openings formed in the central portions of the side frames and passing through the ends of said tie member are vertically disposed bolts or king pins 16.

The central portion of each side frame is provided at its top with a widened portion 17, the same serving as a rest or support for the lower ends of a series of compression springs 18.

A relatively light truck bolster 19, pref-

erably cast, has its end portions formed into spring cap plates 20 which are positioned over and bear directly upon the upper ends of the springs 18, and formed integral with the central portion of each spring cap plate 60 is a depending tubular bearing member 21 which extends downwardly into a cylindrical bearing member 22, the latter projecting upwardly from the center of the corresponding spring supporting plate 17.

Formed at the center of the bolster 19 is a pocket 23 which is occupied by a compression spring 24, the upper end thereof bearing directly against the underside of a body bolster 25 or a part of the car underframe. 70

Formed on or fixed to the undersides of the end portions of the body bolster 25 are pivot bearing plates 26, the same resting in corresponding bearings 27, and which latter are formed on top of the cap plates 20 on 75 the ends of the bolster 19. The upper portions of the bolts or king pins 16 pass through suitably formed apertures in the centers of plates 26, 27 and 17.

By virtue of this construction, the ends 80 of bolster 19 are pivotally connected to the car underframe or body bolster and at the same time they are pivotally connected to the central portions of the side frames 11 and upon which latter they are yieldingly 85 supported by the compression springs 18. This construction is effective in producing the desired degree of flexibility in the truck and while in service and the truck is traversing a curved portion of the track, the bolster 19 will at all times remain at right angles to the longitudinal center line of the car body. At the same time as the truck side frames move radially to accommodate themselves to the curved track, they will 90 also move radially relative to the bolster. This will produce a distorting effect in the springs 18 and when the truck reaches the straight track, these springs will, in tending to return to their normal positions, have 95 a centering effect on the side frames which will restore them to their normal positions parallel with the car body. Any load received by the springs 24 is transferred through the bolster 19 to the truck side 100 frames so that at all times this weight bears upon the wheels at each side of the truck.

In service it sometimes happens that a wheel, or wheels, on one side of the truck will drop into a depression in the track, 110

with the result that these low wheels tend to throw the load on the remaining supports of the car body. My present construction contemplates supporting the car body at its 5 four corners, and if one of these supports is removed, as when a wheel, or the wheels on one side of the truck drop into a depression in the track, then, if the car under-frame or the car body itself is sufficiently 10 stiff and the drop of the wheels is sufficiently far, the supporting spring between the dropped side frame and body bolster either approach or pass the state of exhaustion. In the latter event, the spring 24 serves as 15 a compensating spring and assists in supporting the car at its center. Under ordinary conditions, the springs 24 are "bottled up", and are brought into play to serve as auxiliary supporting springs when any of 20 the main supporting springs at the four corners of the car fail to perform their function or perform it inefficiently.

If the car body was flexible, such, for instance, as an old wooden car body which will 25 weave and twist in service, possibly the corner of the car (which would be unsupported where the car body was sufficiently strong and rigid to carry the load on its three corners) might drop, when the wheels strike 30 a depression in the track, and cause the flanges of the wheels to constantly engage the track thereby preventing derailment. But, if the wheels are held above the track over the depression, where my truck construction is employed, in connection with a 35 rigid car body, then derailment might follow, especially on a curve. To avoid this derailment and to transmit a portion of the load of the car body onto the wheels in a depression in the track, the compensating spring 24 will be brought into action to assist in supporting the load when any set 40 of supporting springs fails to adequately perform its function.

45 It will be readily understood that minor changes in the size, form and construction of the various parts of my improved car truck can be made and substituted for those herein shown and described, without departing from the spirit of my invention, the 50 scope of which is set forth in the appended claims.

I claim:

- 55 1. In a car truck, the combination with a pair of side frames, of a bolster pivotally connected to said side frames, yielding pressure means interposed between the side frames and said bolster and yielding pressure means bearing on top of said bolster.
- 60 2. In a car truck, a pair of side frames, a bolster pivotally connected to said side frames, yielding pressure means interposed between the side frames and said bolster, and a spring interposed between said bolster and 65 a part of the car body.

3. In a car truck, a pair of side frames, a bolster having its end portions pivotally connected to and yieldingly supported upon said side frames, bearing plates pivotally arranged on the end portions of said bolster, 70 and means for tying said bearing plates, bolsters, and side frames to each other.

4. In a car truck, a pair of side frames, a bolster having its end portions pivotally connected to and yieldingly supported upon 75 said side frames, bearing plates pivotally arranged on the end portions of said bolster, means for tying said bearing plates, bolsters, and side frames to each other, and yielding pressure means bearing on top of said 80 bolster between the bearing plates.

5. In a car truck, a pair of side frames, a bolster having its ends formed to receive springs, the same being pivotally connected to the side frames, springs interposed between the side frames and bolster, and a 85 spring interposed between the bolster and a part of the car body.

6. In a car truck, a bolster yieldingly arranged beneath a car body and having its 90 ends pivotally supported thereupon, truck side frames pivotally connected to the end portions of said bolster and adapted to swing in horizontal planes, and springs interposed between said side frames and 95 bolster.

7. The combination of a bolster pivotally arranged beneath the car body, truck side frames pivotally arranged beneath the end portions of the bolster, wheels and axles, 100 yielding means between the bolster and said side frames, and expansion means between the bolster and the car body whereby when the wheels reach a depression in the track, said expansion means tend to force the 105 wheels to follow the track.

8. In a car truck, a pair of side frames, a bolster yieldingly and pivotally arranged beneath a car body, coöperating means between said side frames and the end portions 110 of the bolster, which coöperating means constitutes a bearing to permit the side frames to swing in horizontal planes, and yielding pressure means arranged between said side frames and bolster.

9. In a car truck, a pair of side frames, a bolster, coöperating means between said side frames and the end portions of the bolster, which coöperating means constitutes a bearing to permit the side frames to swing 120 in horizontal planes, yielding pressure means arranged between said side frames and bolster, and a spring arranged on the bolster for yieldingly supporting a portion of the weight of the car body carried by the 125 truck.

10. In a car truck, a pair of side frames, a bolster supported by said side frames, a plurality of pivotal bearing plates between said bolster and the car body and yielding 130

pressure means between said bolster and the car body, which yielding pressure means is located between said pivotal bearing plates.

11. In a car truck, a pair of side frames, 5 a bolster pivotally connected to said side frames, yielding pressure means interposed between the side frames and said bolster, and a plurality of pivotal bearing plates between said bolster and the car body.

12. In a car truck, a pair of side frames, 10 a bolster yieldingly supported thereupon, pivotal bearing plates between said bolster and the car body, and a spring interposed between said bolster and the car body.

In testimony whereof I hereunto affix my 15 signature this 16th day of July, 1919.

CHARLES T. WESTLAKE.
